UNITED STATES PATENT OFFICE.

FRANK H. RICKARDS, OF CENTRALIA, ILLINOIS.

STAMPING-MACHINE.

SPECIFICATION forming part of Letters Patent No. 730,970, dated June 16, 1903.

Application filed March 13, 1903. Serial No. 147,639. (No model.)

To all whom it may concern:

Be it known that I, FRANK H. RICKARDS, a citizen of the United States, residing at Centralia, in the county of Marion and State of Illinois, have invented a new and useful Stamping-Machine, of which the following is a specification.

The invention relates to certain improvements in stamping-machines, and has for its principal object to provide a mechanism of simple construction adapted especially for the stamping of names or trade-marks on the soles or heels of footwear.

A further object of the invention is to provide a hand-stamp of this character in which the stamping members will have an extensive separating movement for convenience in placing the article to be stamped in position and in which the die member will be uppermost and be held in a stationary position, so that the operator may readily determine the exact position at which the stamp is to be applied.

A still further object of the invention is to provide a hand-power stamping-machine by which increased leverage may be gained and the effective power gradually increased toward the end of the stamping operation.

With these and other objects in view the invention consists in the novel construction and arrangement of parts hereinafter described, illustrated in the accompanying drawings, and particularly pointed out in the appended claim, it being understood that various changes in the form, proportions, size, and minor details of the structure may be made without departing from the spirit or sacrificing any of the advantages of the invention.

In the accompanying drawings, Figure 1 is a longitudinal sectional elevation of a stamping-machine constructed in accordance with my invention. Fig. 2 is a plan view of the same.

The frame of the machine comprises a base 1, from which rise a hollow standard 2 and a curved overhanging arm 3. At the upper end of the arm 3 is a vertical opening 4 for the reception of the shank 5 of a die or stamping member 6, the latter being provided with raised letters or other devices to be stamped in the soles of shoes or in other articles. The shank 5 is vertically adjustable in the open-

ing 4 and may be locked in any desired position by means of a set-screw 6, and a number of interchangeable dies may be employed in connection with each machine.

The coöperative stamping member is in the form of a disk 7, which, if the stamped matter is to be embossed, may be provided with either raised or depressed lettering to correspond with that on the upper die 6. The die member 7 is secured to the upper end of a vertically-adjustable stem 8, guided in the hollow standard 2, and the lower end of said stem is recessed, as indicated at 9, for the reception of the upper end of a reversely-curved link 10, which is pivotally connected to the stem 8 by a pin 11.

In the lower portion of the hollow standard are suitable openings forming bearings for a transverse shaft 12, to which is rigidly secured a rocker-arm 13, pivotally connected, by a pin 14, to the lower end of the link 10, and in order to form an extensive bearing for the shaft the frame is extended at one side of the hollow standard to form a boss or sleeve 15, having its end terminating at or beyond the edge of the base 1. To the outer end of the shaft 12 is secured one end of a handled operating-lever 16, a locking-key 17 and set-screw 18 being employed to hold the parts rigidly together.

In using the machine the article to be stamped is placed over the die member 7 and the operating-handle is turned to revolve the shaft 12 and raise the stem 8 through the rocker-arm-and-link connection until the article being operated upon is pressed between the two stamping members. As the upper stamping member 6 is stationary, the operator may readily guide the article to proper position, and thus impress the stamp at any desired point.

It will be observed that the pin-and-rocker-arm connection permits extensive movement of the lower die member and that during the latter portion of the stamping operation, when the most power is required, the rocker-arm 13 and link 10 will be nearly in vertical alignment, so that the exercise of comparatively slight pressure on the operating-lever will effect a slow but extremely powerful thrust on the stem 8 to complete the stamping operation, while the extensive guiding-surface

afforded the stem by the hollow standard 2 will prevent lateral movement of the lower stamping member.

Having thus described the invention, what is claimed is—

The combination in a stamping-machine, of the base, a vertically-disposed hollow standard forming a part of the base, a curved arm projecting upwardly from said base and having a vertically-disposed opening at its upper end, an adjustable die member having a shank portion fitting within said opening, a set-screw for engaging and locking the shank portion in adjusted position, a stamping member 15 7 of a diameter greater than the opening of the standard and resting on the top of said standard when in inoperative position, a stem 8 guided within the hollow standard and carrying said stamping member, a boss or 20 sleeve projecting laterally from the lower

portion of the standard and having an opening forming an extensive supporting-bearing, a rock-shaft 12 fitting within said bearing-opening, an operating-lever secured to the outer end of said rock-shaft, a crank-arm 13 25 secured to the inner end of said rock-shaft, and a curved link connecting said crank-arm to the lower end of the stem 8, the rock-shaft and stem being so arranged with respect to each other that a portion of the rock-shaft 30 lies in the vertical plane of the stem, substantially as specified.

In testimony that I claim the foregoing as my own I have hereto affixed my signature in the presence of two witnesses.

FRANK H. RICKARDS.
